UNITED STATES PATENT OFFICE.

SAMUEL A. HOLMES, OF STORM LAKE, IOWA.

LATRINE-SEAT SHIELD.

1,077,277.

Specification of Letters Patent. Patented Nov. 4, 1913.

Application filed February 13, 1913. Serial No. 748,168.

To all whom it may concern:

Be it known that I, SAMUEL A. HOLMES, a citizen of the United States, residing at Storm Lake, in the county of Buena Vista and State of Iowa, have invented a new and useful Latrine-Seat Shield, of which the following is a specification.

The present invention relates to latrine seat shields, and aims to provide a novel and improved device of this character adapted to be applied to the seat in a novel and efficient manner and to serve as a protection against contagion.

With the foregoing and other objects in view which will appear as the description proceeds, the invention resides in the combination and arrangement of parts and the details of construction hereinafter described and claimed, it being understood that changes in the precise embodiment of the invention herein disclosed can be made within the scope of what is claimed without departing from the spirit of the invention.

The invention has been illustrated in the accompanying drawing, wherein:

Figure 1 is a plan view of a shield. Fig. 2 is a perspective view thereof as applied to the seat.

Referring specifically to the drawing, the shield comprises a blank of suitable paper or other material, which may be oiled or otherwise treated with sterilizing or anti-septic agents. This blank has been designated by the numeral 3 and is of a contour slightly larger than the seat in order to properly cover the entire space. The blank is provided with a central opening 4 and an inwardly projecting guard flap 5, which flap is adapted to be folded downward in back of the front end of the seat. The blank is also provided with a relatively wide and short flap 6 at its front end provided with

an elongated transverse slot 7, thereby forming a flat U-shaped strap terminally attached to the forward end of the blank.

In use, the shield may be readily placed on the seat, the flap 5 being folded inwardly in rear of the front end of the seat, and the flap or strap 6 being folded over and below the front end of the seat, so that it will be held between the front end of the seat and the front end of the bowl or hopper. The strap may thus pass readily below the front end of the seat, the opening or slot 7 accommodating the front end of the seat to permit of the folding of the flap or strap under the seat. The strap and the flap 5 thus retain the shield in position, and the shield as a whole provides a suitable protection against contagion, as will be apparent.

The shield may be inexpensively manufactured for individual use, and may be folded if desired in order that they may be better stored, shipped or carried about.

Having thus described the invention, what is claimed as new is:

1. A latrine seat shield comprising a blank having a flap to fold under the front end of the seat with a slot in the flap to accommodate the front end of the seat.

2. A latrine seat shield comprising a blank having a flap to fold under the front end of the seat with a slot in the flap to accommodate the front end of the seat, and having a guard flap to fold in back of the front end of the seat.

In testimony that I claim the foregoing as my own, I have hereto affixed my signature in the presence of two witnesses.

SAMUEL A. HOLMES.
